(57) **CLAIM**

The ornamental design for a fishing gimbal, as shown and described.

DESCRIPTION

FIG. 1 is a front perspective view of a first embodiment of a fishing gimbal;

FIG. 2 is a rear perspective view thereof;

FIG. 3 is a top view thereof;

FIG. 4 is a bottom view thereof;

FIG. 5 is a left side view thereof;

FIG. 6 is a right side view thereof;

FIG. 7 is a front view thereof;

FIG. 8 is a rear view thereof;

FIG. 9 is a front perspective view of a second embodiment of the fishing gimbal;

FIG. 10 is a rear perspective view of the second embodiment of the fishing gimbal;

FIG. 11 is a top view of the second embodiment of the fishing gimbal;

FIG. 12 is a bottom view of the second embodiment of the fishing gimbal;

FIG. 13 is a left side view of the second embodiment of the fishing gimbal;

FIG. 14 is a right side view of the second embodiment of the fishing gimbal;

FIG. 15 is a front view of the second embodiment of the fishing gimbal;

FIG. 16 is a rear view of the second embodiment of the fishing gimbal;

FIG. 17 a front perspective view of a third embodiment of the fishing gimbal;

FIG. 18 is a rear perspective view of the third embodiment of the fishing gimbal;

FIG. 19 is a top view of the third embodiment of the fishing gimbal;

FIG. 20 is a bottom view of the third embodiment of the fishing gimbal;

(Continued)

FIG. 21 is a left side view of the third embodiment of the fishing gimbal;
 FIG. 22 is a right side view of the third embodiment of the fishing gimbal;
 FIG. 23 is a front view of the third embodiment of the fishing gimbal; and,
 FIG. 24 is a rear view of the third embodiment of the fishing gimbal.
 The broken lines depict portions of the fishing gimbal that form no part of the claimed design.
